UNITED STATES PATENT OFFICE.

PHILLIPP F. FLAGGE, OF MILWAUKEE, WISCONSIN, ASSIGNOR TO MILWAUKEE CORRUGATING COMPANY, OF GREENFIELD, WISCONSIN, A CORPORATION OF WISCONSIN.

INSIDE CORNER-BEAD.

1,361,843.

Specification of Letters Patent. Patented Dec. 14, 1920.

Application filed August 14, 1916. Serial No. 114,688.

To all whom it may concern:

Be it known that I, PHILLIPP F. FLAGGE, a citizen of the United States, residing at Milwaukee, in the county of Milwaukee and State of Wisconsin, have invented certain new and useful Improvements in Inside Corner-Beads, of which the following is a specification, reference being had to the accompanying drawing, forming a part thereof.

This invention relates to sheet metal corner beads and plastering guides or gages for reentrant angles of plastered walls.

The main objects of the invention are to obtain true reentrant angles at the intersections of plastered walls; to facilitate the application of plaster adjacent to such angles; to avoid the cracking of the plaster in and adjacent to such angles by the shrinking, swelling, warping and settling of the wood or other ground work or foundation of the walls; and generally to improve the construction of metallic corner beads of this class.

It consists in the construction, arrangement and combination of parts as hereinafter particularly described and pointed out in the claims.

In the accompanying drawing like characters designate the same parts in both figures.

Figure 1 is a cross section on the line 1—1, Fig. 2, of a corner bead embodying the invention as applied to intersecting plastered walls, and Fig. 2 is a perspective view of a portion of the bead by itself as viewed from the inner side thereof.

The bead consists of a continuous strip of sheet metal formed integrally with spaced or separated nailing or attachment wings *a*, disposed at an angle to each other corresponding with the angle formed by the walls to which the bead is to be applied, inwardly bent offsets or offset portions *b*, substantially perpendicular to the wings, and oppositely folded gage flanges *c*, continuous with the inner meeting edges or portions of the offsets and forming a reentrant angle whose sides are parallel with the wings. The offsets *b* form an angular longitudinal recess in the back of the bead directly behind the flanges *c* and opposite the corner angle formed by the intersection of the walls to which the bead is applied. The offsets *b*, which are brought together or meet

at or adjacent to their junction with the folded flanges *c*, facilitate the springing of the wings *a* to readily adapt them to the lath *d* or other foundation to which the bead and plaster *e* are applied, as shown in Fig. 1, and the recess *f* formed by the offsets in the back of the bead, leaving a quadrangular space between it and the lath *d* or other plaster foundation, greatly facilitates placing and fastening the bead in position as it avoids contact with the lath *d* or other plaster foundation at the angle formed by the intersecting walls where obstructions such as splinters, are apt to occur in the rough unfinished foundation work for the plaster. This recess or space also allows for the formation of clenches on the coating of plaster, which is pressed in applying the same, through openings *b* formed in the wings *a*, and extending into the offsets *b*, as shown. The folded flanges *c*, form gages or guides for a trowel or other instrument used in applying the plaster, and determine the proper thickness of the coating, which is applied flush with the inner faces of the flanges, as shown in Fig. 1. The folding of the metal to form the gage flanges, which are exposed on their inner faces flush with the plaster, forms a comparatively stiff reentrant angle, which will maintain its true shape, springing or yielding of the offsets *b* permitting the wings *a* to conform or adapt themselves to any shrinking, swelling, warping or settling of the lath or other foundation to which the bead is attached, without causing the plaster to crack at or adjacent to the bead. The recesses between the wings *a* and the overhanging flanges *c* parallel therewith, receive and hold the plaster and permit the adjacent coatings separated by the intervening parts of the bead, to slip or move relatively to each other in accordance with relative movement of the intersecting foundation walls, without cracking, breaking or injuring the plaster or bead. The offsets *b* can bend or spring from or toward each other, to allow for any ordinary shrinking, swelling, warping or settling of the wood or other ground work for the plaster, without cracking the plaster or affecting its attachment to the ground work.

Each of the wings *a* of the bead is preferably cut or formed into ears *h*, separated from one another by corresponding inden-

2
tations alternating with the ears and indentations of the other wing, as shown in Fig. 2, so that the ears of other beads may be cut from the indentations on either side or both sides of each bead with the least possible waste of material.

The bead is cut and rolled or pressed into the required shape in continuous strips or sections of any desired length.

- 10 10 The wings *a* or ears *h* are formed with holes *i*, for nails *j*, or the like, by which the bead is fastened to the lath and studing or other ground work for the plaster, as shown in Fig. 1.
- 15 15 Modifications in details of construction of the bead may be made without departure from the principle and scope of the invention as defined in the following claims.

I claim:

- 20 20 1. An inside corner bead consisting of a continuous strip of sheet metal formed integrally with attachment wings separated from each other at their adjacent edges by a clear space and disposed at an angle to each other corresponding with the angle formed by the intersection of the walls to which the bead is to be applied, inwardly bent offset portions substantially perpendicular to the wings, and folded two-ply gage flanges 30 parallel with and overhanging the wings and forming a reentrant angle at their intersection.
- 25 25 2. An inside corner bead consisting of a continuous strip of sheet metal formed integrally with attachment wings separated from each other at their adjacent edges by a clear space and disposed at an angle to each other corresponding with the angle formed by the intersection of the walls to 35 which the bead is to be applied, inwardly bent offset portions substantially perpendicular to the wings and forming a reentrant angle at their intersection.
- 30 30 3. An inside corner bead consisting of a continuous strip of sheet metal formed integrally with attachment wings separated from each other at their adjacent edges by a clear space and disposed at an angle to each other corresponding with the angle formed by the intersection of the walls to 40 which the bead is to be applied, inwardly bent offset portions substantially perpendicular to the wings and forming a reentrant angle at their intersection.

the wings, brought together along their inner edges and forming an angular recess in the back of the bead, and oppositely folded two-ply gage flanges overhanging and substantially parallel with the wings and forming a reentrant angle at their intersection. 45

3. An inside corner bead consisting of a continuous strip of sheet metal formed integrally with attachment wings separated from each other at their adjacent edges by a clear space and disposed at an angle to each other corresponding with the angle formed by the intersection of the walls to which the bead is to be applied, inwardly bent offset portions substantially perpendicular to the wings, brought together along their inner edges and forming an angular recess in the back of the bead, and oppositely folded two-ply gage flanges continuous with 50 the inner edges of the offsets and forming a reentrant angle whose sides are parallel with and overhang the wings, the offsets being formed with clench openings. 55

4. An inside corner bead consisting of a continuous strip of sheet metal formed integrally with attachment wings separated from each other at their adjacent edges by a clear space and disposed at an angle to each other and each comprising a series of 60 ears separated from one another by corresponding indentations alternating with the ears and indentations of the other wing, inwardly bent meeting offsets substantially perpendicular to the wings and forming a 65 longitudinal recess in the back of the bead, and oppositely folded two-ply gage flanges continuous with the meeting portions of the offsets and forming a reentrant longitudinal angle whose sides are parallel with and overhang the wings. 70

PHILLIP F. FLAGGE.
